ELECTRICAL CONNECTOR DEVICE

Filed Dec. 31, 1947

FIG. 2.

FIG. I.

INVENTOR
GEORGE M. MIERLEY

BY 3.3.3

ATTORNEY

UNITED STATES PATENT OFFICE

2,471,440

ELECTRICAL CONNECTOR DEVICE

George M. Mierley, Havertown, Pa., assignor to
Westinghouse Electric Corporation, East Pitts-
burgh, Pa., a corporation of Pennsylvania

Application December 31, 1947, Serial No. 795,083

1 Claim. (Cl. 174—59)

1 This invention relates to electrical connector devices, and has for an object the provision of an improved protected connector assembly for joining sections of cable.

It is another object of the invention to provide an improved cable connector device adapted to connect the outer end of one section of cable which is carried within a casing structure to the end of an exteriorly disposed section of cable which is adapted to be carried closely adjacent the surface of the casing structure.

More particularly, it is proposed to provide an electrical connector device for connecting adjacent ends of a cable associated with an aviation gas turbine engine or the like, wherein elements of the device necessarily exposed on the wall of the engine casing are of minimum elevation and are carried closely adjacent the surface thereof, so as to maintain the desired streamlined contour of the casing and to facilitate mounting of the engine in an aircraft.

A further characteristic of the invention is the provision of a protected electrical connector device which is adapted to be carried on the engine casing for detachably connecting an internally disposed cable section to an exterior cable section supported on the casing at an angle with respect to the internal cable, the device having a housing adjustable to accommodate the outer cable in several different positions without necessitating the breaking of any soldered joints.

These and other objects are effected by the invention as will be apparent from the following description and claim taken in connection with the accompanying drawings, forming a part of this application, in which:

Fig. 1 is an elevational sectional view of an electrical connector device constructed in accordance with the invention;

Fig. 2 is a top plan view of the device shown in Fig. 1, the cover section thereof being broken away; and

Fig. 3 is an elevational end view of the device shown in Fig. 1, taken substantially along the line III—III thereof.

Referring to Fig. 1 of the drawing, a connector device constructed in accordance with the invention and generally indicated at 10 is shown in association with a casing structure 11 of an engine or other apparatus that is equipped with an electrical cable, including an internally mounted inner cable section 12 and an exterior cable section 13, the latter being disposed substantially parallel to the surface 11a of the casing and normal to the adjacent cable section 12. Both cable

2

sections 12 and 13 carry suitable insulation 14, which is cut away to expose the respective ends 12a and 13a thereof. As shown in the drawing, the end 12a of the inner cable extends through a bore 15 formed in the casing structure 11, and terminates substantially flush with the surface of the structure. Secured to the cable 12 is a binding post member 17 having a sleeve portion 18, which is adapted to receive the exposed end 12a of the cable and to admit solder by way of a suitable slot 19. A tubular insulator member 20 is interposed between the wall of the bore 15 and the outer surface of the sleeve portion 18, the inner end of the insulator member being adapted to 15 abut to a shoulder 22 of the casing and the outer end of the insulator member being adapted to engage an annular collar 23 which is formed on the binding post 17 outwardly of the bore 15. The outer end of the binding post member 17 terminates in a screw-threaded stud portion 25, which extends substantially along the axis of the member.

The end of the outer cable 13 is provided with a terminal lug 27, having a sleeve portion fitted 25 over the exposed end 13a of the cable and suitably clamped or deformed at 28 to insure a tight joint. The outer end of the lug 27 is compressed or otherwise formed to provide an off-set flat eye portion 30 having an aperture 31 which is adapted 30 to receive the screw-threaded stud 25 of the binding post 17. The eye portion 30 is formed substantially along a plane tangent to the surface of the lug 27 opposite the deformed portion 28, and is adapted to engage the upper surface of 35 the collar 23 carried by the binding post 17.

The lug 27 is adapted to be secured to the binding post 17 by means of a nut 40, which has screw-threaded connection with the stud portion 25 and may be locked in place by means of a suitable 40 locking nut 41. For facilitating assembly of the device, the stud portion 25 is provided with a slot 42 into which a tool may be inserted for preventing undesired rotation of the binding post 17 when the nut 40 is applied thereto.

45 For shielding the adjacent ends of the cable sections 12 and 13, there is provided a housing section, indicated generally at 35, which includes a substantially rectangular body portion 36 having a chamber 37 formed therein for containing 50 the outer end of the binding post 17, and a channel portion 3 which is adapted to extend substantially parallel to the surfaces 11a of the casing structure and to underlie a short length of the outer cable 13. For insulating the lug 27, there is 55 provided a split insulator sleeve comprising sec-

tions 39a and 39b, the section 39a being disposed within the channel portion 38 as best shown in Fig. 1.

A closure member or cover 45 is provided for completing the connector assembly and comprises a substantially rectangular portion 46 having a surface 47 engageable with a complementary surface 48 formed on the housing 35, and a channel portion 48' similarly engageable with the corresponding surface of the channel portion 38 for retaining the section 39b of the split insulator bushing enclosing the lug 27. A plurality of mounting bolts 50 are provided for securing the cover 45 and housing 35 in place on the casing structure 11, these bolts being adapted to pass through suitably registering bores formed in the corner portions of the cover 45 and housing 35 for engagement in corresponding threaded bores 50a provided in the casing structure 11. It is preferred to space the bores 50a which are adapted to receive the respective bolts 50 at equally distant points, as shown in Fig. 2, so as to permit the housing 35 and cover to be disposed in the most convenient angular position with respect to the axis of the binding post 17. In this way the connector device may readily be adjusted to facilitate installation of the engine including the casing structure 11 in different types of aircraft, it being understood that the position of the outer cable 13 may differ in accordance with individual structural conditions.

From the foregoing it will now be seen that with the elements of the improved connector device assembled as just explained, the binding post 17 may be soldered to the end of the inner cable 12 in a preliminary operation without regard to the angle at which the associated end of the cable section 13 may be brought in. When the casing structure 11 is subsequently installed in an aircraft and the cable section 13 prepared for attachment, the housing 35 may be installed at the most convenient angle for receiving the lug 27, and the cover 45 then secured in place, all without breaking the soldered connection or otherwise altering the condition of the inner cable 12 and binding post 17. By reason of the provision of the split insulator bushing sections 39a and 39b within the channel portions 38 and 48', in surrounding relation with respect to the lug 27, any accidental strain on the outer cable 13 will effectively be resisted and prevented from accidental grounding of the connection.

While the invention has been shown in but one

form, it will be obvious to those skilled in the art that it is not so limited, but is susceptible of various changes and modifications without departing from the spirit thereof.

What is claimed is:

The combination with a casing structure having an opening adapted to contain an inner cable section and associated with an adjacent outer cable section adapted to be disposed along the surface of said casing substantially normal to said inner cable section, of an electrical connector of the character described comprising an insulating bushing fitted into said opening, a binding post member having a sleeve portion received in said bushing and secured over the end of said inner cable, said binding post member having a collar portion abutting said end of said insulator bushing and an outwardly projecting screw-threaded stud portion, a lug secured to the end of said outer cable section and having an off-set terminal portion apertured to receive said stud portion of the binding post member and engageable with said collar portion, locking nut means for detachably securing said lug to said binding post member, a split insulating bushing for protecting said lug portion, a housing carried on said casing structure having a body portion for enclosing said binding post member and a channel portion adapted to underlie the adjacent end of said outer cable section, a cover section adapted to close said housing section and including a channel portion cooperative with the first-named channel portion for retaining said split bushing and said lug, and a plurality of fastening means cooperative with said housing and casing structure, said fastening means being equally spaced to facilitate mounting of said housing to accommodate said outer cable section in the most convenient angular position relative to the axis of said binding post.
